COMBINATION KNIFE AND WRENCH SET

Emil S. Polk, New York, N. Y.

Application September 23, 1953, Serial No. 26,920

Term of patent 14 years

(Cl. D22—3)

Figure 2 is a perspective view thereof as it appears with the elements in closed position;

The side opposite that disclosed in Figures 1 and 2 is substantially similar to the side shown on those figures.

I claim:

The ornamental design for a combination knife and wrench set, as shown and described.
